TREATMENT OF HYDROCARBON OILS

Filed Sept. 9, 1931

UNITED STATES PATENT OFFICE

2,008,480

TREATMENT OF HYDROCARBON OILS

Claude W. Watson and Victor Stapleton, Port Arthur, Tex., assignors to The Texas Company, New York, N. Y., a corporation of Delaware

Application September 9, 1931, Serial No. 561,826

4 Claims. (Cl. 196—58)

This invention relates to the treatment of hydrocarbon oils for the production of solid or semi-solid residues such as coke or pitch and contemplates a process in which the charging stock is introduced into a fractionating zone receiving vapors evolved in a residue-forming zone and a residual product formed in the fractionating zone is introduced into the residue-forming zone, while highly heated oil which may comprise an extraneous stock introduced to the system or a cycle stock obtained in the process is also introduced into the residue-forming zone wherein the desired pitch-forming or coke-forming temperature is maintained.

One aspect of the invention relates to a process in which hydrocarbon oil is treated in a combined cracking and distilling or polymerizing operation to form as ultimate products a light distillate and a heavy residual component and contemplates a process in which a suitable cracking stock is subjected to conditions for conversion into light products, such as gasoline, and a heavy or residual material, present as a reaction product of the cracking or as an extraneous charging stock introduced to the system, may be converted to an ultimate residue of the nature of pitch or coke.

The invention has in view a process in which fresh charging stock is brought into contact with heated products that have been subjected to a cracking reaction, the products of cracking and the fresh charging stock being subjected to distillation or fractionation to form a condensate which constitutes a cycle stock that is cycled through the cracking zone. The invention contemplates a process in which the vapors evolved in the ultimate residue-forming zone may be subjected to fractionation in a plurality of sections, while fresh charging stock is brought into contact with the evolved vapors in the first section of the fractionating zone to thus form an admixture of reflux condensate and charging stock which is directed into the final residue-forming zone while the vapors that are delivered from the first section of the fractionating zone are delivered to a second fractionating section in which fractionation occurs, with the formation of a condensate which is cycled through a cracking zone, which preferably assumes the form of a high temperature heating coil, and the hot products obtained in cracking this cycle stock are directed to the final residue-forming zone.

The cycle condensate that is obtained in the second section of the fractionating zone is a clean condensate uncontaminated with any residual

products that may be contained in the charging stock directed to the first portion of the fractionating zone, and this clean condensate may well be subjected to relatively high cracking temperatures and to conditions adapted for the formation of light products of high anti-knock value without undue coke formation. The high temperature to which this clean stock may be heated facilitates the maintenance of a sufficiently high temperature in the final residue-forming zone to effect the desired distillation and polymerization of the other constituents that are introduced into this zone without the necessity of applying additional heat at this point.

Cracked residues that are withdrawn from cracking stills may contain greater or less proportions of light distillate such as gasoline, together with heavier constituents, which may be generally referred to as gas oil constituents, which are adapted for further cracking. It is desirable to strip such residue and subject the gas oil constituents to further cracking, but these residues are very difficult to handle in subsequent distillations, due to the fact that they contain large quantities of polymerized constituents or compounds that are readily converted into coke upon heating. In accordance with our invention a cracked residue, such as is withdrawn from a pressure cracking still, which may or may not have been subjected to a subsequent distilling operation to remove a portion of the vaporizable constituents, may be brought into contact with the vapors evolved in a final residue-forming operation, so that the cracked residue charging stock serves to reflux the hot vapors, and the resultant commingled cracked residue and condensate is then directed to the residue-forming zone. The vapors that pass beyond this primary refluxing operation are subjected to a further fractionating operation and a condensate formed in this secondary fractionation is cycled through a high temperature heating zone wherein the cycle stock is brought to a relatively high cracking temperature, after which the hot products are discharged into the final residue-forming zone. In a preferred method of operation the stream of commingled charging stock and reflux condensate from the primary fractionating zone is merged with the stream of secondary condensate emerging from the high temperature cracking zone and the combined stream is passed into the final residue forming zone. Thus the high carbon-forming cracked residue may be effectively subjected to sufficient heat to remove the vaporizable con-

stituents and form a heavy residue which preferably assumes the form of a pitch or coke.

In order to obtain the maximum yield of gasoline or other light distillate from a given charging stock, it is necessary that the stock be reduced to an ultimate pitch or coke residue with the subjection of the intermediate fractions to the cracking reaction for conversion into the desired light product. A difficulty that has been encountered in reducing the stock to this ultimate pitch or coke residue has been the inability to control the operation so as to obtain the particular residual product desired. Thus, for example, if it is intended to produce a pitch, it has been difficult to prevent the formation of large quantities of coke with the pitch, and similarly if it is intended to run to dry coke it has been impossible to control the operation so accurately that at least considerable portions of the coke product will not contain a large pitch or hydrocarbon component.

In accordance with our invention the heavier or residual constituents are brought into contact with a stream of condensate maintained at a higher temperature than that of the heavy or residual constituents, in such a way that an accurate control of temperature may be had so as to obtain the product desired. In some cases the products from the primary fractionating zone, that is, the commingled fresh charging stock and reflux condensate from that zone, may be cooled and the stream of oil thus cooled merged with the highly heated cycle condensate undergoing cracking so as to thus obtain the exact composite temperature desired. The invention also contemplates that in some cases, instead of introducing the fresh charging stock to the fractionating zone, that it may be introduced directly into the stream of highly heated cycle condensate undergoing cracking, the commingled stream being directed into the final residue forming zone to effect distillation and polymerization to produce the pitch or coke product desired. In some cases a portion of the charging stock may be introduced into the fractionating zone, while the other portion is directed into the stream of hot cycle stock passing to the residue forming zone.

In order to more fully explain the invention reference will now be had to the accompanying drawing which is a flow diagram showing a preferred embodiment of the invention.

In the apparatus thus illustrated a furnace 10 adapted for supplying heat to the heating coils employed, a vaporizing or coking chamber 11, a primary fractionating tower 12 and a secondary fractionating tower 13 are shown. A pump 14 is adapted to introduce fresh charging stock through a line 15 having manifold branch lines as 15a and 15b to the primary fractionating tower 12. It is to be understood that the fresh charging stock may be introduced into the tower 12 at any suitable point therein. The character of the charging stock employed and other variable conditions will determine the precise point in the tower at which the charging stock is introduced. Thus, for example, in case the charge consists of a very heavy or dirty residuum, such as a crude residuum or cracked residue, it is generally preferable to introduce such a material at a mid-point or lower point in the tower and in such case it is preferable to provide merely baffle plates in the lower portion of the tower over which the liquid may flow, while if desired bubble trays may be employed in the upper portions of the tower.

A vapor line 16 conducts vapors from the tower 12 to the tower 13. A line 17 serves for with-

drawing condensate from the tower 13 to a hot oil pump 18 having a discharge line 19 extending to a coil 20, positioned in the furnace 10. It is ordinarily preferable to subject the reflux condensate as introduced by the line 19 to the maximum amount of cracking that can be obtained in the heating coil without danger of excessive coke formation, and to accomplish this it is preferable to provide the coil with a soaking section wherein the desired cracking temperature may be maintained.

In the apparatus illustrated the coil 20 is intended to be in a convection portion of the furnace and an extension or continuation of this coil is indicated comprising wall tubes to form a radiant section 21. It is to be understood that various coil heating arrangements may be employed in the practice of the invention. A radiant section 21 such as indicated is of advantage in maintaining the high cracking temperature desired while avoiding the danger of direct flame impingement or of excessive heating by direct current of convection gases. In general it is desirable that the latter portion of the coil in which the oil is heated in the furnace 10 be disposed in a zone of comparative low heat density adapted to produce a more or less soaking effect. A transfer line 22 extends from the coil 21 to a manifold line 23 having a plurality of branch lines as 23a, 23b, 23c, extending to the coking drum 11. A valve 24 is indicated in the transfer line which may be employed as a pressure reducing valve as is hereinafter more fully explained.

A line 25 is provided for withdrawing combined charging stock and reflux condensate from the tower 12 to a pump 26 having a discharge line 27. The line 27 is branched to form one line 28 having further branches, such as 28a, 28b, extending directly to the coking drum 11, and another branch line 29 which extends to the transfer line 22.

When introducing heated condensate from the coil 21 mixed with bottoms from the tower 12 through the transfer line 22 it is preferable to distribute the charge entering the coking drum 12 through branch lines 23a and 23c, and when passing oil from tower 12 through line 28 it is preferable to introduce the oil from line 28 through the upper branch line 28a while introducing hot oil from the transfer line 22 through the lower branch line 23c. In other words, we employ the upper lines 23a and 28a and the lower line 23c instead of the intermediate lines 28b and 23b.

We prefer that the streams of vapor or liquid entering the coke drum, more particularly those introduced to the upper or intermediate sections thereof, be directed downwardly and thus may provide downwardly depending outlets 23x and 28x for the branch lines 23a and 23b, and 28a and 28b, respectively. The streams of entering fluid may thus be discharged downwardly toward the surface of the liquid in the coke drum thus tending to beat down or dissipate any foam produced in the coking operation and cleanse the upwardly rising vapor of any foam that may be carried therewith. In this way the constituents in the coking drum 11 may be reduced to a coke or pitch residue without priming.

A cooling coil 33 is indicated having appropriate valued connections to the line 27 so that when desired the hot products withdrawn from the tower 12, or a portion thereof, may be cooled a predetermined degree before being introduced

either directly into the coking drum 11 or to the transfer line 22 to be thus mixed with the stream of highly heated products flowing to the coking drum.

5 The charging line 15 is shown provided with additional branch lines 31 and 32 communicating with a coil 33 positioned in an economizer section of the furnace 10, so that a portion or all of the fresh charging stock may be preheated to a predetermined degree. In lieu of the economizer coil 33 the fresh charging stock may be preheated in various other ways, such for example as by passing it in heat exchange with hot condensates withdrawn from the towers 12 or 13. The charging line 15 is also shown with a branch line 34 which extends directly to the transfer line 22, so that the charging stock, instead of being admitted to the tower 12, may be passed directly to the transfer line, or so that a portion of the fresh charge may be passed directly to the transfer line while the other portion is introduced to the tower 12. A branch line 35 is also indicated for connecting the charging line 15 at a point therein ahead of the branch line 31 so that in cases where charging stock is being passed through the heating coil 33 a portion of the cool or unheated charging stock may be passed directly through the lines 35 and 34 to the transfer line 22. It will thus be seen that by means of the connecting lines shown all of the charging stock may be introduced to the tower 12, or all of the charging stock may be introduced directly to the transfer line 22 through line 34, or the charging stock may be apportioned between the tower 12 and transfer line 22, and in either case a portion or all of the charging stock may be heated in the economizer coil 33 or otherwise, as has been indicated.

40 A vapor line 36 is shown for conducting vapors from the coking still 11 to the primary fractionating tower 12. A line 37 is indicated for withdrawing a liquid residue from the still 11. A bottom manway 38 is shown for the purpose of coke removal when running to coke, and a well 39 is shown adapted for suitable coke boring apparatus. When running to a pitch residuum, a hot residue in liquid form may be withdrawn through the line 37 during a run; the pitch solidifies upon cooling and may be subsequently pulverized and used as a powdered fuel or otherwise utilized. When running to coke it is preferable to have a plurality of coke drums 11. Thus the transfer line 22 may be manifolded to a plurality of drums which can be cut into succession during a run, and while the coke is removed from one drum another drum may be employed for the formation of coke.

55 A vapor line 40 is shown extending from the fractionating tower 13 to a condenser coil 41 and a receiver 42 is indicated for collecting the final distillate.

60 A line 43 is shown interconnecting the lines 17 and 25 so that if desired a portion of the reflux condensate collected in the tower 13 may be added to the liquid withdrawn from the tower 12 for introduction to the transfer line 22 or to the coking still 11. The line 43 is shown as being connected to a cooling coil 44 and reflux pump 45 so that if desired a portion of the condensate from the tower 13 may be cooled and employed as a reflux to the upper portion of the tower 12 to control the fractionating operation in the tower. Cooling means may also be applied to the tower 75 13, such as for example a portion of the final dis-

tillate collected in the tower 42 may be refluxed to the top of the tower 13.

5 In addition to the charging stock introduced by the pump 14 provision is also made for introducing additional charging stock as by means of a pump 46 having a discharge line 47 connected to the line 19, or the additional charging stock may be introduced into the tower 12, as by providing the pump 45 with a line 48 extending to a suitable source of charging stock. Thus for example, an extraneous gas oil stock may be charged by pump 45 while a residuum stock is charged by pump 14.

10 In practicing the invention, charging stock may be admitted directly to the fractionating tower 12 or may be passed through the preheating coil 33 before being admitted to the fractionating tower. When the preheating coil is used the degree of heating may be dependent upon the nature of the stock with respect to its liability to form coke and also may be limited by the extent of cooling that it may be desired to apply to the tower 12. Thus, for example, charging stocks such as gas oil and crude residuum may well be heated to temperatures of 400° F. 15 to 650° F. or even higher in the preheating coil 33 before being admitted to the tower. In the case of cracked bottoms withdrawn either from pressure stills, or from stripping stills in which pressure still residues have been stripped, it is 20 particularly undesirable to apply any very high temperature heating to such oil while flowing to the coking chamber. These cracked residues contain polymer products of cracking which are readily converted to coke and gas at temperatures 25 even below those at which any appreciable formation of gasoline may take place and consequently these residual oils should not be subjected to high enough temperature in the coil 33 as would engender the formation of excessive coke deposits there- 30 in. As a rule, we prefer to introduce the cracked residual oils directly into the tower 12 without passing them through the preheating coil 33. In one method of operation contemplated the cracked stock may be drawn directly from running tanks 35 receiving residue from cracking stills or from stripping stills and the residue at temperatures say of 200° F. to 300° F. passed directly to the tower 12.

40 The charging stock introduced to the tower 12 operates to cool the hot vapors derived from the coking drum 11 and is subjected to fractionation or distillation therein so that any lighter constituents present may be distilled off while the residual constituents, which may be combined 45 with a certain amount of condensed constituents from the vapors received from the coking drum, collect as a combined residue and condensate in the lower part of the tower and are withdrawn by the pump 26 by which the bottoms from the 50 tower are introduced directly to the coking still 11 either through line 28 and one or more of the branch lines 28a and 28b or by the line 29 to the transfer line 22 to be thus commingled with the stream of highly heated oil flowing from the coil 55 21 to the coking still 11.

55 The vapors that pass from the tower 12 to the tower 13 are subjected to fractionation therein and the clean reflux condensate that is thus obtained in the tower 13 is withdrawn by 60 the pump 48 and is subjected to cracking in passage through the coils in the furnace 10. The highly heated products from the heating coils are combined either in the coking still 11, or in the transfer line 22 before entering the still, with 65 75

the residual products from the tower 12. It is advantageous to pass the bottoms from the tower 12 through the line 29 to the transfer line 22 since this method of operation facilitates a very accurate control of conditions in the coking still 11. Temperature indicating means may be inserted in the transfer line 22 beyond the point at which the two streams are merged so that it is thus possible to obtain an extremely accurate control of the temperature and hence of the conditions under which distillation and polymerization take place in the drum 11. By varying the amount of oil introduced to the tower 12 either as charging stock through the line 15, or as additional cooling supplied by the reflux condensate pump 45, the quantity as well as the temperature of the bottoms obtained in the tower 12 may be regulated and consequently the extent of cooling applied to the coking drum may be accurately controlled and this cooling may be further controlled by passing a portion or all of the bottoms withdrawn from the tower 12 through the cooling coil 30 or by the direct introduction of fresh charging stock through the line 34 to the transfer line 22. By these means, coupled with the control of the high temperature stream leaving heating coils in the furnace 10, an accurate regulation of the conditions of polymerization and distillation may be maintained in the coking drum 11.

When it is desired to run to a pitch residue the proper temperature conditions dependent upon the character of the material introduced in the drum 11 is maintained so that a pitch residue of desired melting point is formed which may be continuously withdrawn through the line 37 by which the pitch may be conducted to suitable cooling and collecting means in which the pitch is solidified.

When it is desired to run to a coke residue the liquid in the drum 11 instead of being withdrawn during the run is retained in the drum and a coking temperature is maintained therein so that the mass is converted to a coke residue. We have found that it is desirable to distribute the oil introduced to the coking drum instead of introducing all of the oil to the drum at one point. For example, in case the entire charge of oil to the drum is introduced at the bottom, particularly when charging heavy cracked residues, there is danger of priming tarry materials through the vapor line 36 into the tower 12. On the other hand, when introducing all of the charge to the upper portion of the drum it is practically impossible to run to a dry coke. When, however, in accordance with our invention, the material is distributed by introducing the material at different points in the drum the tendency to priming may be largely avoided and at the same time a dry coke may be produced. Thus, for example, when the stream of material entering from the transfer line 22 to the header 23 and comprising bottoms from the tower 12 commingled with highly heated cracked products from the coil 21 is introduced to the drum 11 say through the branch lines 23a and 23c, the distribution of the charge to the drum in this way serves to maintain the requisite conditions for coking throughout the mass in the drum while at the same time avoiding priming. It is advantageous and in fact practically necessary if a dry coke is to be produced to establish and maintain a current of upwardly rising vapors through the mass in the coke drum which can well be accomplished by the presence in the ma-

terial introduced to the lower part of the drum of the highly heated cycle stock leaving the coil 21.

When the bottoms that are withdrawn from the tower 12 are mixed in the transfer line 22 with the stream of oil flowing from the coil 21 it is desirable to so regulate the quantity and temperature of the stream of bottoms flowing through the line 29 to the transfer line 22 that the temperature of the commingled stream will be sufficiently reduced, dependent on the rate of flow through the transfer line, that coking may be avoided in the transfer line. When the charging stock which is introduced by the pump 14 to the tower 12 comprises an oil that is very readily coked, such as cracked residue, and when such an oil is commingled with the stream of highly heated oil passing from the coil 21 to the transfer line 22, care must be taken to keep the temperature of the commingled stream down below a point at which coking would occur in the transfer line and connections leading to the coke drum. This reduction in temperature may be facilitated by the introduction of cool oil into the transfer line 22 through line 34.

One advantageous method of operation, particularly when treating cracked residues, is to introduce the bottoms withdrawn from the primary tower 12 through the line 28 and upper branch line 28a, either with or without cooling in the coil 30, while introducing the highly heated and cracked cycle stock from the coil 21, and transfer line 22 through the branch line 23c; in this way the heavier stock containing residual components is introduced into the drum 11 at a point above that of the introduction of the more readily vaporizable cycle stock from the secondary tower 13 and heating coils 20 and 21 and thus the establishment and maintenance of a current of upwardly rising vapors through the mass in the coking chamber is insured so that the heavier hydrocarbons which would otherwise form pitch pockets in the coke mass as it is formed may be readily distilled out while the mass in the drum maintained at coking temperatures is thus converted to a dry coke.

By retaining the liquid in the coking drum 11 and maintaining the mass at coking temperature, vapors are evolved and heavy complex hydrocarbon constituents are polymerized to form a coke residue. The introduction to the lower part of the coking drum of highly heated vaporizable constituents (which are present either in the combined stream of cracked products from coil 21 and the bottoms from tower 12, when such bottoms are introduced into the transfer line and a portion or all of the combined stream directed into the lower part of the coking chamber, or when the cracked products from the coil 21 are passed through the line 22 without admixture with the bottoms from tower 12) serves the purpose not only of maintaining the necessary distilling and polymerizing temperature to form the coke residue but also provides an upwardly rising current of vapor which facilitates the removal of the very heaviest hydrocarbon components which would otherwise tend to form pitch pockets in the coke mass and thus facilitates the production of a dry coke. The control of the cooling that is applied to the coking drum 11 may be accomplished by regulating the temperature and quantity of the bottoms that are withdrawn from the tower 12 and supplied to the coking drum either through the lines 28 or 29 or with such added cooling as the direct intro-

duction of relatively cool oil to the transfer line 22 from the line 34. The coking operation may thus be accurately controlled in the drum 11 so that while a dry coke may be produced the coke 5 may not be so hard as to unduly impede the subsequent removal of the coke from the drum at the end of a run to a given coking drum. Hitherto it has been difficult to produce a dry coke which would meet the tests desired as to 10 volatile content without unduly baking the coke residue to form a hard coke mass which was extremely difficult to remove from the coking chamber. The practice of our invention has overcome this difficulty by providing for the production of a dry coke which is yet of a sufficiently 15 soft nature that it may be readily removed from the coking drum.

The oil which is heated in the coils 20 and 21 may be passed through these coils under any 20 suitable super-atmospheric pressure that may be desired for cracking, such for example, as a pressure of several hundred pounds and the temperatures may range within any suitable range for cracking although we prefer to employ temperatures of the order of 900° F. to 1000° F. since temperatures of this order are advantageous in imparting the desired anti-knock quality to the final distillate, are sufficiently high to maintain the desired pitch-forming or coke-forming temperature in the still 11 and by reason of the clean character of stock charged through these coils 30 may be employed without the formation of excessive coke deposits in the coil 21. The coking or pitch-forming still 11 is held at a moderate superatmospheric pressure such as a pressure of the order of 50 or 100 pounds and when higher pressures are employed in the coil 21, which is usually the case, the pressure should be correspondingly reduced in the coking drum 11 as by 40 means of the pressure reduction valve 24.

In the practice of our invention any suitable charging stock which may be desired to crack may be introduced by the charging pump 14 to the primary fractionating tower 12. Thus, for 45 example, a gas oil charging stock may be employed and the stock converted to a gasoline distillate and a coke or pitch residue as ultimate products. The practice of our invention is, however, particularly adapted for the treatment of 50 residual petroleums having a high carbon content.

In further explanation of the invention, a specific example may be given in which the charging stock as introduced by the pump 14 is a 55 cracked residual product derived from a previous cracking operation. In this example of the invention residue is withdrawn from a pressure cracking still, subjected to a stripping operation and then introduced by the pump 14 through the line 15 at the rate of fifty barrels per hour to the fractionating tower 12 at a temperature of about 200° F. The tower 12 is refluxed with gas oil to maintain an overhead temperature of about 700° F. while combined residue and condensate is withdrawn from the bottom of the 60 tower at a temperature of about 800° F. The tower 13 is supplied with a naphtha reflux to maintain an overhead temperature of about 400° F. and a bottom temperature of about 630° F. Clean cycle condensate is withdrawn from the 65 bottom of tower 13 at the rate of about 260 barrels per hour and subjected to cracking in the coils in the furnace 10 under about 200 pounds pressure with a temperature in the outlet of the 70 coil 21 of about 925° F. The bottoms from the 75 coil 21 and the stream of cracked products from the coil 21 are directed into the coking drum 11 wherein a temperature of about 860° F. at 120 pounds pressure is maintained. Liquid is retained in the drum 11 and at that temperature the mass is readily converted to a coke residue.

In accordance with our invention it is not necessary to employ excessively high temperatures in the coking drum. We have found that with a wide range of charging materials satisfactory results may be obtained within a temperature range extending from a minimum of about 820° F.-825° F. up to a maximum of about 850° F.-860° F. or 875° F. While the practice of the invention does not preclude the use of higher temperatures we are able to produce a marketable coke within the temperature range indicated so that there appears to be no necessity for going to higher temperatures. Thus, at the minimum temperatures indicated (about 825° F.) such materials as crude 20 residual stocks (reduced crudes) and reduced sludge fuel (a product recovered from acid sludge produced in treating oil with sulphuric acid) may, in accordance with our invention, be satisfactorily treated to produce a coke substantially free from 25 pitch pockets and of a sufficiently low content of volatile combustible matter to meet market requirements. The higher range of temperature mentioned is well adapted for the treatment of certain of the more refractory stocks such as a gas 30 oil product derived from a previous coke stilling operation.

We find that the higher the temperature employed in the coke drum and the longer the length of time employed in running to coke in a given 35 drum, the harder will be the resultant coke and the greater the difficulty of removing the coke at the end of a run. We have, for example, produced a coke having 10% to 12% volatile combustible matter which was easily removed from 40 the coking drum and produced an excellent pulverized fuel. A coke containing a lower content of volatile combustible matter will tend to be harder and give more difficulty in removal from the coking drum and furthermore is not so satisfactory for use as a pulverized fuel. However, 45 in accordance with our invention, the operating conditions in the coking drum may be accurately controlled and may be varied so as to obtain a coke product having the particular characteristics desired.

We prefer to carry on the fractionation in the secondary tower 13 in such a manner that the condensate that is drawn off through the line 17 will be suitable for high temperature cracking. 55 By carefully regulating the fractionating operation as carried on in the fractionating towers 12 and 13, more particularly by properly refluxing the tower 12 so as to prevent the carrying over to the tower 13 of potential coke-forming constituents. By the use of the condensate or cycle stock from the tower 13 not only may the gasoline yield be increased, but the increased temperature of the cracked products delivered to the drum 11 facilitates the maintenance of the desired pitch-forming or coke-forming temperature therein even when admitting to the drum comparatively large quantities of relatively low temperature material. The bulk of the heat required for the coking operation may be supplied by the stream 60 of highly heated products from the cracking coil and consequently material, such as heavy residual material, may be admitted to the coking chamber, or to the transfer line leading thereto, at temperatures below a coking temperature, sufficient 65

heat for coking being maintained by the stream of highly heated products from the cracking coil.

It is advantageous to maintain a relatively large reservoir of liquid condensate in the bottom 5 of tower 13 in order to give a high degree of flexibility in the manipulation of pump 18.

A feature of our invention is the means of controlling the temperature not only in the coking drum 11 but also in the transfer line 22 and connections leading to the coking drum. We have found that at temperatures usually around 975° F. and higher considerable difficulty may be encountered in operating valves in the lines through which the oil at this high temperature is flowing. 10
15 In accordance with our invention the stream of oil at temperatures for instance of the order of 900° F. to 1000° F. may enter the transfer line 22 from the heating coil 21 but the temperature of the stream may be lowered, either by the stream of oil from the line 29 or by the stream of oil from the line 34 or by both such streams of oil, to lower the temperature sufficiently that the valves, such as those in lines 23a, 23b and 23c may be readily operated. One great difficulty that has been 20
25 encountered in coking operations has been in diverting the stream of hot oil from one coking chamber into another coking chamber. In the practice of our invention, by reason of the cooling oil admitted into the stream of hot oil ahead 30
35 of the valves, this diversion of the stream may be readily accomplished. It may be noted that the lines 34 and 29 are shown as being connected with the transfer line 22 beyond the valve 24. When there is a considerable drop in pressure through
40
45 the pressure reducing valve 24 this arrangement may be employed, since the liquid may be more easily introduced at this point than on the higher pressure side of the valve. However, our invention contemplates the introduction of the cooling liquid when necessary on the pressure side of the valve 24 as well.

Obviously many modifications and variations of the invention, as hereinbefore set forth, may be made without departing from the spirit and scope thereof, and therefore, only such limitations should be imposed as are indicated in the appended claims.

We claim:

1. A combined cracking and coking process for 50
55
60
65
70
75
converting hydrocarbon oil into a light distillate and coke as final products that comprises passing a stream of condensate oil through a heating coil to subject the oil to cracking temperature, passing the thus heated stream of oil to a coking chamber where distillation takes place, removing evolved vapors from the coking chamber while retaining the liquid therein, passing the vapors withdrawn from the coking chamber successively to primary and secondary fractionating zones, introducing fresh charging stock into the system, passing a portion thereof into the primary fractionating zone, withdrawing combined condensate and unvaporized charging stock from the primary fractionating zone and introducing same into the coking chamber, passing another portion of the fresh charging stock introduced into the system into the stream of highly heated oil passing from said heating coil at a lower temperature than said stream to thus reduce the temperature thereof, withdrawing condensate from the secondary fractionating zone and delivering it to said heating coil, maintaining the mass in the coking chamber at a coking temperature to thereby convert the same to a coke residue and taking off an overhead distillate from the

secondary fractionating zone to constitute the final light distillate.

converting hydrocarbon oil into a light distillate and coke as final products that comprises passing a stream of condensate oil through a heating coil to subject the oil to cracking temperature, passing the thus heated stream of oil to a coking chamber where distillation takes place, removing evolved vapors from the coking chamber while retaining the liquid therein, passing the vapors withdrawn from the coking chamber successively to primary and secondary fractionating zones, introducing fresh charging stock into the system, passing a portion thereof into the primary fractionating zone, withdrawing combined condensate and unvaporized charging stock from the primary fractionating zone and introducing same into the stream of highly heated oil passing from said heating coil at a lower temperature than said stream to thus reduce the temperature of the oil delivered to the coking chamber, passing another portion of the charging stock introduced into the system into the stream of oil passing from said heating coil at a lower temperature than said stream to reduce the temperature of the oil, withdrawing condensate from the secondary fractionating zone and delivering it to said heating coil, maintaining the mass in the coking chamber at a coking temperature to thereby convert the same to a coke residue and taking off an overhead distillate from the secondary fractionating zone to constitute the final light distillate.

3. A combined cracking and coking process for 35
